US00D907742S

(12) **United States Design Patent** (10) **Patent No.:** **US D907,742 S**
Camp et al. (45) **Date of Patent:** **** Jan. 12, 2021**

(54) **WATER PURIFICATION MEDIA DEVICE**(71) Applicant: **Unger Marketing International, LLC**,
Bridgeport, CT (US)(72) Inventors: **Robert Camp**, Bethany, CT (US); **Paul Adams**, Monroe, CT (US); **Stephen Huda**, Shelton, CT (US)(73) Assignee: **UNGER MARKETING INTERNATIONAL, LLC**, Bridgeport,
CT (US)(**) Term: **15 Years**(21) Appl. No.: **29/717,830**(22) Filed: **Dec. 19, 2019****Related U.S. Application Data**(63) Continuation-in-part of application No. 29/639,519,
filed on Mar. 7, 2018.(51) **LOC (13) Cl.** ..... **23-01**(52) **U.S. Cl.**USPC ..... **D23/207**; D7/400; D7/667(58) **Field of Classification Search**USPC D23/207-209; D7/213, 397, 399, 400,
D7/667; 426/81; 210/459; D1/121, 130CPC B65D 85/043; B65D 65/466;
B65D 85/808; A47J 31/08

Primary Examiner — Marianne N Pandozzi(74) *Attorney, Agent, or Firm* — Cantor Colburn LLP(57) **CLAIM**

The ornamental design for the water purification media device, as shown.

DESCRIPTION

FIG. 1 is a top perspective view of a water purification media device showing our new design;

FIG. 2 is a side perspective view thereof;

FIG. 3 is a bottom perspective view thereof;

FIG. 4 is a top plan view thereof; and,

FIG. 5 is a bottom plan view thereof.

1 Claim, 5 Drawing Sheets# US D907,742 S
